UNITED STATES PATENT OFFICE.

WILLIAM A. CLARK, OF BOSTON, MASSACHUSETTS.

SPLIT PULLEY.

SPECIFICATION forming part of Letters Patent No. 656,944, dated August 28, 1900.

Application filed December 7, 1899. Serial No. 739,477. (No model.)

To all whom it may concern:

Be it known that I, WILLIAM A. CLARK, a citizen of the United States, and a resident of Boston, county of Suffolk, State of Massachusetts, have invented an Improvement in Split or Divided Pulleys, of which the following description, in connection with the accompanying drawings, is a specification, like characters on the drawings representing like parts.

This invention has for its object the production of a strong and durable split or divided pulley of simple and cheap construction, possessing great rigidity and stiffness when in place on a shaft, readily applicable to or removable from its shaft or other supporting-journal, and light in weight.

In carrying out my invention I preferably make the face or belt-receiving portion of the pulley of sheet metal of the requisite width and of a length corresponding to the desired circumference of the pulley, the thickness of the sheet depending on the diameter of the pulley. This piece or strip is bent into an annular form, and its ends are united to the outer ends of two separable arms, the inner ends of said arms being united in suitable manner to the interior of the face portion midway between its ends. Two semicircular stiffening and supporting webs are attached throughout their length to the face portion and at their ends to the arms, the latter at their inner ends being contiguous. Midway between their ends the arms are oppositely concaved to form seats which receive the shaft or a bushing interposed between them and the shaft, as desired, the spring or elasticity of the face portion permitting the separation of the outer ends of the arms when applying or removing the pulley. The width of the arms is preferably equal to the width of the face portion to provide greater strength and stiffness, and the arms are also preferably provided each with one or more stiffening-flanges extending from one to the other end thereof. The arms for this purpose may be T-bars or channel-irons, the latter being preferable for large pulleys.

A pulley constructed in accordance with my invention is very stiff, strong, and light in weight and it can be made at a very low cost.

Various novel features of my invention will

be hereinafter described, and particularly pointed out in the following claims.

Figure 1 is a perspective view of a divided pulley embodying one form of my invention, the arms of the pulley being separated. Fig. 2 is a similar view of another embodiment of my invention to be described. Fig. 3 is a side elevation of the pulley shown in Fig. 1, illustrating the manner in which the pulley may be conveniently applied to the shaft by means of an interposed bushing. Fig. 4 is a partial sectional detail on the line xx , Fig. 3. Fig. 5 is a perspective detail of one of the ends of the arm shown in Figs. 1 and 3, and Fig. 6 is a similar detail of a channel-iron arm illustrated in Fig. 2.

In constructing a pulley in accordance with my present invention I form the face or belt-receiving portion F of a strip of sheet metal of the desired thickness and width and of a length corresponding to the circumference of the pulley to be made, said face portion being bent into annular form, but not united at its ends, and is preferably a single piece. I prefer also for the sake of increasing the stiffness and strength of the face portion to provide the same at its longitudinal edges with inturned flanges f. (See Figs. 1, 3, and 4.)

Two semicircular and oppositely-located supporting-webs F^x are secured to the inner face of the annular part F of the pulley, preferably by means of a lateral flange f^x on the outer circumference of each web riveted or otherwise permanently secured, as at 5, Fig. 1, to the belt-receiving portion F to stiffen and support the latter throughout the length of the two webs, the latter, as best shown in Fig. 3, closely approaching each other at their ends when the pulley is in place upon a shaft or other journal on which it is to be mounted.

The free ends of the face or belt-receiving portion F of the pulley are attached to the outer ends of two separable arms A, preferably by riveting said face portion to outwardly-turned transverse lips or flanges a^x (see dotted lines, Fig. 1) by suitable rivets 6, (see Figs. 3 and 4,) the inner or opposite ends of the arms being brought together as near as possible and also having outturned transverse flanges a^x (see dotted lines, Fig. 1) to be riveted to the inner surface of the

belt portion F. The spring or elasticity of the sheet-metal face portion of the pulley will normally maintain it in the position shown in Fig. 1, with the outer ends of the 5 arms separated; but when the pulley is in place upon a shaft the arms will be brought together, as shown in Fig. 3, and held clamped upon the pulley, as will be described. Between their ends the arms are provided with 10 oppositely-concaved seats a to receive directly the shaft or a bushing interposed between the shaft and the seats, if desired, as shown in Fig. 3, and the portions a' of the arms adjacent their ends are in alignment, so 15 that when the pulley is clamped in position such parts a' of the arms will impinge one upon the other, being held in such clamped position by suitable bolts 7, Fig. 3, extended through suitable holes 8 in the arms and held 20 in place by check-nuts 9.

Between the straight portions a' of the arms and the seats said arms are bent to diverge toward the center of the pulley, as at a², so that when the pulley is in position, as 25 in Fig. 3, said divergent portions a² of the arms can be drawn toward each other by suitable clamping-bolts c^x to firmly clamp the pulley upon its shaft or other device to which it is to be attached. This construction 30 provides for a certain springiness of the arms, permitting a very tight clamping of the pulley in place, yet by very simple means.

The ends of the supporting-webs F^x are 35 preferably secured to the arms, and in order to increase the strength and stiffen the arms longitudinally I prefer to provide them each with one or more longitudinal ribs running from one to the other end thereof substantially on their outer sides, a single stiffening 40 rib or flange, as a⁵, being shown in Figs. 1, 3, and 4, the supporting-webs F^x being attached to the stiffening-rib by rivets 10. The arm shown in said Figs. 1, 3, and 4 is substantially a T-iron which can be conveniently 45 used for the purpose, and the pulley so constructed will be sufficiently stiff for moderate diameters.

It will be manifest that a pulley constructed as hereinbefore set forth will be very light 50 in weight, strong and durable, yet very rigid, and capable of easy application to or removal from a shaft.

In Fig. 3 I have shown a bushing B interposed between the shaft B^x and the seats a in 55 the pulley-arms, such bushing being of any suitable construction—such, for instance, as shown in my United States Patent No. 634,260, granted October 3, 1899.

For pulleys of large diameter and wide faces 60 I prefer to employ the construction shown in Figs. 2 and 6, the belt-receiving or face portion H being shown as a preferably non-flanged strip of sheet metal of suitable length, width, and thickness bent into annular form, 65 with its ends disconnected, and each half of the belt-receiving portion provided with a plurality of supporting-webs H^x, two being

herein shown as secured to each diameter of the face portion by suitable rivets or other fastenings 12, extended through the face portion and through lateral flanges h^x on the outer circumferences of the supporting-webs. The separable arms D in this embodiment of my invention are made as channel-irons having longitudinal stiffening-flanges d^x 70 extended from one to the other end thereof along their edges and riveted or otherwise secured, as at 15, to the ends of the supporting-webs H^x, the arms in their general characteristics otherwise being the same as the 80 arms A, hereinbefore described, they being provided with seats d and divergent portions d², through which the clamping bolts or devices are extended. In the construction 85 shown in Fig. 2 each half of the divided pulley is substantially a box-truss, giving a most rigid, strong, and durable construction, combined with light weight. The ends of the arms D are outturned to form transverse lips or flanges d⁶ (best shown in Fig. 6,) and riveted to the face portion, as hereinbefore described. The width of the arms in either of the constructions shown will be preferably 90 as nearly as possible equal to the width of the face portion of the pulley. It will be 95 manifest from the foregoing description that the springiness or elasticity of the face portion of the pulley permits the opening or closing of the same. An inspection of Fig. 2 will reveal the slight separation of the adjacent ends of the flanges h^x of the supporting-webs H^x when the pulley is open or unclamped, as at 300, adjacent the contiguous inner ends of the arms D.

While I have herein shown two practical 105 embodiments of my invention, I have not attempted to show or describe the various changes or modifications which may be made in the construction of the same without departing from the spirit and scope of my invention, and accordingly my invention is not restricted to the precise construction and arrangement herein shown and described.

Having described my invention, what I 110 claim as new, and desire to secure by Letters 115 Patent, is—

1. A split pulley comprising a one-piece, transversely-divided face portion, two opposite, semicircular sheet-metal supporting-webs flanged along their outer edges and connected 120 throughout their length with the face portion, and two separable arms connected at their ends with the face portion and also attached to the ends of the webs.

2. A split pulley comprising a one-piece, 125 transversely-divided face portion, two opposite, semicircular supporting-webs connected throughout their length with the face portion, and two separable sheet-metal arms connected at their ends with the face portion and 130 also attached to the ends of the webs, each arm having a stiffening-flange, extended from one to the other end thereof.

3. A split pulley comprising a transversely-

- divided face portion, two opposite, semicircular supporting-webs connected throughout their length with the face portion, and two separable arms connected at their ends with the face portion, each arm having a stiffening-flange extending from one to the other end thereof, and the ends of the supporting-webs being attached to said stiffening-flanges. 5
4. A metallic split pulley comprising a one-piece, transversely-divided sheet-metal face portion, two opposite, semicircular supporting-webs connected throughout their length with the face portion, and two separable arms rigidly secured at each end to the face portion and also to the ends of the said webs. 10
5. A split pulley comprising a transversely-divided face portion, two opposite semicircular supporting-webs, flanged along their outer edges and connected thereat with the face portion, and two longitudinally-flanged, separable arms connected with the semicircular supporting-webs. 15
6. A split pulley comprising a one-piece, transversely-divided face portion, two opposite semicircular supporting-webs connected throughout their length with the face portion, and two separable arms having oppositely-concaved seats and connected at their ends with the face portion, the ends of the supporting-webs being also attached to said arms. 20
7. A metallic split pulley comprising a transversely-divided sheet-metal face portion, two opposite, semicircular supporting-webs connected throughout their length with the face portion, and two separable arms having outwardly-bent transverse flanges at their ends to which the face portion is attached, each arm having a longitudinal stiffening-flange on its outer face. 25
8. A split pulley comprising a one-piece, transversely-divided sheet-metal face portion, two sheet-metal arms having central, oppositely-concaved seats and straight ends, rigidly secured at each end directly to the face portion, the arms diverging from their straight ends to the seats, and semicircular supporting-webs interposed between the face portion and the arms and attached to each. 45
9. A split pulley comprising a transversely-divided sheet-metal face portion, two spring-arms rigidly connected at both of their ends with the face portion and having oppositely-concaved seats, and a semicircular supporting-web interposed between each arm and the face portion, each web being flanged along its outer edge and attached to the face portion throughout the length of the flange. 50
10. A split pulley comprising a transversely-divided sheet-metal face portion, two spring-arms rigidly connected at both of their ends with the face portion and having oppositely-concaved seats the arms diverging toward said seats, a semicircular sheet-metal supporting-web interposed between each arm and the face portion and attached to the latter throughout the length of the web, and means mounted upon the divergent portions of the arms to draw them together and thereby clamp the pulley upon a shaft or other support. 55
11. A split pulley comprising a face or belt-receiving portion disconnected at its ends, a plurality of pairs of semicircular supporting-webs secured to the two halves of the face portion, and arms provided with seats and rigidly connected with the face portion and the pairs of supporting-webs, an arm and its attached pair of webs together with the corresponding half of the face portion of the pulley constituting substantially a box-truss. 60
